CLAMP FOR CONCRETE FORMS

Joseph W. Keffer, Ligonier, Pa.

Application February 27, 1943, Serial No. 477,407

1 Claim. (Cl. 144—291)

This invention is an improvement in clamps for concrete forms, of the general type disclosed in my prior Patents Nos. 1,590,033 and 1,765,235. As therein shown and described, and as here, the objects in view are to effect accurate adjustment of the confining walls surrounding the pouring cavity. Ordinarily such walls are of vertically arranged planks or the like, as in column formation, usually re-assembled after use.

The patents noted utilize successive series of double pairs of pivotally connected members or arms, adapted to be laid around the exterior generally rectangular surface contour of the forms, having edgewise contact by successive sets of pairs with the forms, and accurately tightened thereagainst. The free ends of the arms cross each other, in under and overlapping arrangement, at diagonally opposite corners, diagonally between their alternating pivot or hinge connections. Such construction admits of easy application and removal, together with the adjusting and connecting elements, called bearing blocks.

Such bearing blocks are slidably mounted in duplicate on the clamping arms for mutual co-operation, at said diagonally opposite corners, and are effective in thrusting each of the several arms longitudinally and inwardly edgewise, for final correct positioning against the forms.

The tightening adjustment is effected by wedging strains, urging each block of a cooperating pair inwardly along its particular clamping arm, and against the companion cross arm, each of such arms being one of a pivotally connected pair. Simultaneously a reverse outward pulling strain is exerted on each such arm, tending to set the hinge joint terminals accurately around and against the corners of the forms, edgewise.

The present construction utilizes the provision of so constructing the blocks as to avoid confusion or error in application to the arms, and to secure interaction between pairs of blocks, generally as disclosed heretofore. The present improvement embodies additional important features of construction and operation, as herein-after described. Such features relate to strengthening bracing reinforcement of the blocks and to features of construction facilitating identification of their accurate placement, in use.

In the drawings:

Fig. 1 is a somewhat diagrammatic plan view, illustrating my improved block construction, in operative positions;

Fig. 2 is an enlarged detail plan view showing a corner assembly of the working members in position;

Fig. 3 is a longitudinal vertical sectional view on the line III—III of Fig. 2;

Fig. 4 is a perspective view of one of the bearing blocks;

Figs. 5 and 6 represent a part sectional view like Fig. 3, and an end view respectively, illustrating comparative positions of a pair of blocks, for co-operation with the free ends of clamping arms, crossing at different levels.

Generally stated, the invention is particularly adapted to the problem of adjusting the molding forms for square or other rectangular concrete constructions, as columns or pillars. In such operations, the aggregate is poured into a shape-defining cavity within confining and molding walls 2.

These are usually of wooden planks or other suitable material, arranged vertically and requiring exterior confining and bracing elements for adjustment and continuously proper placement.

For such purpose I utilize series of duplicate sets, consisting of pairs of flat metal arms or bars 3, 3a, each pair being pivotally connected at 4, for corner engagement. These pivotally connected arms are arranged as shown, loosely around the forms, with the free end portions of one arm of a pair over or underlapping the end portion of the arm of the other pair, at diagonally opposite corners.

As thus placed, the inner edges of the several arms confront and loosely engage the outer surfaces of the forms, and are tightened by wedging strains through the instrumentality of the pairs of blocks A, A, located in position on the bars 3 and 3a, as in Fig. 1. Each block is a duplicate of the other, and may be placed slidably along its bar 3 or 3a, with either of its top and bottom faces upwardly, the blocks being equally operative in either position.

Each block is operatively related to the other, in side face contact by either pair, when assembled on the free ends of the converging bars, and thrust together, as shown in Fig. 1.

Obviously, one of said bars being laid over the other, as 3 over 3a, or vice versa, the duplicate blocks of a pair will occupy slightly variable positions vertically, corresponding to the upper and lower planes of the bars, such variation ordinarily equalling the thickness of one bar.

Each block A is provided from end to end, with a longitudinal channel or freely open slide-way 5, midway of its vertical thickness, for slideable mounting on its bar, in either position.

Likewise the front end of each block is provided with a transverse clearance opening 6, ex-

tending inwardly beyond the upper and lower corner terminals 7, to a depth approximating say one-half the width of an over or underlapping bar, lying transversely thereof.

Clearance 6 terminates in rear upper and lower abutment faces 8, 8, and the upper and lower front extensions of each block provide substantial transverse housing covering for the arm of the companion block.

The active inner end portion of the block is formed to provide receding vertical faces 9—9a, extending rearwardly from apex 7, at right angles as shown, either of said faces being adapted to closely confront the co-acting corresponding face of the companion block of the other bar, as in Figs. 1 and 2.

Because of the difference in levels of the two blocks when mounted on their different level arms, one of the co-operating pair of blocks will be slightly higher, or vice versa, from the other, to an extent corresponding to the thickness of either of the arms 3 and 3a. The vertical height of faces 9—9a, while amply sufficient to effect good contact with the corresponding faces of the co-acting block, will however involve a slight extension vertically of one block and its top, and of the other block and its bottom, or vice versa, slightly beyond the other, as in Figs. 5 and 6, in either mounting.

Wedging adjustment of each block and its companion block, of both pairs inwardly along their respective crossed arms, operating at diagonally opposite corners, and with the block faces 9—9a of each pair confronting and eventually abutting, exerts a pulling strain on bars 3 and 3a. Such action results in tightening the faces of the bars inwardly of pivoted corner joints 4, against the form corners, with simultaneous pressure of each bar 3a and 3 edgewise throughout its contacting length against the outer flat form surfaces, by inward pressure of abutments 8.

The gradual adjustment of each block on its bar, and with relation to the companion block of a pair, is generally like that disclosed in my prior patents, supra. Thus the upper and lower wall portion of each block is provided with variably spaced longitudinal slots 10, in alinement with and above and below the middle passageway 5, for arm 3 or 3a.

Each arm is likewise provided with a series of similar variably spaced slots 11, registering longitudinally more or less with slots 10, providing clearance and resisting bearings for movement imparting power, by the wedge 12, inserted through any available registering slots.

As the wedges are driven, each block is urged inwardly along its arm, with simultaneous reverse tightening of the arm for snug placement of the outer pivotally connected corner connections.

Simultaneously also, one or other of abutments 8 forces the bar of the companion block edgewise against the form, all of these several functions being performed gradually, to finally and accurately set the form walls to exact desired positions.

It is especially important in such operations to finally bring the blocks together in firm resisting contact by their contacting side faces 9—9a. These as shown are amply broad, long and continuous, rearwardly from the apex 7 by upper and lower reduced but amply wide width faces 9 and on the same plane as the full width rear faces 9a.

These faces make firm slightly overlapping bearing contact with each other throughout, however placed on the arms.

Extension of the top and bottom walls and faces 9 clear to the terminals 7, not only greatly increases such surface contact, but also ensures ample bracing engagement with the corresponding faces of the other co-acting block.

The construction likewise provides an immediate condition tending to indicate any variation from correct positioning of the companion blocks. Thus, when the two outer non-contacting surfaces 9—9a are in perfect alinement, as on the line x, x, with their apices 7 coinciding, the operator may at a glance, or by a straight edge, decide affirmatively that both blocks of either pair are in correct normal position, or the reverse.

Otherwise, if there is the slightest variation, proper correction may be made, by adjustment of either block, to such common plane.

These features of the invention are important, time saving, and tend to easy and immediate correction of any variation from perfect relative positions. They greatly contribute to economy of time in correctly adjusting the blocks for best performance, and in maximum efficiency by greatly added strength, of the invention in use.

The improved construction generally is of great and added advantage in effecting perfect and satisfactory application and use of the clamps, which heretofore have been subject to a certain material degree of insufficient surface contact, and of undesired variation from perfect positioning.

It will be understood also that the arms are to be provided with proper limiting abutments, as 13, preventing endwise removal of their blocks rearwardly, and that the wedges may conveniently be connected with the blocks, as by chains 36 of prior Patent No. 1,765,235.

Also that the size and dimensions of the blocks, preferably made of cast metal, their engaged arms, and the several elements involved may be varied or modified, depending upon the size, shape, proportions, etc., of the moulding forms, or otherwise changed in detail construction, within the scope of the following claim.

What I claim is:

50. A pair of integral clamping blocks for use at the crossing of two frame holding arms in a column clamp, each block having a pair of vertical contact faces diverging rearwardly at right angles from a corner junction, a through longitudinal passage extending midway of the vertical thickness of the block and adapted to receive a frame holding arm, a cut-out portion intermediate the ends of said corner junction, said cut-out portion extending transversely across the end of the block and being of greater depth than said passage so as to provide arm-edge engaging abutments above and below the front terminal of the longitudinal passage and also to provide upper and lower arm-side engaging portions extending forwardly from said abutments to said corner junction, said arm engaging portions above and below said cut-out portion forming vertical side faces at right angles to each other extending backwardly from the junction and merging into full depth faces beyond said abutments.

JOSEPH W. KEFFER.
